(57) **CLAIM**

The ornamental design for a suture bridge, as shown and described.

DESCRIPTION

FIG. 1 is a front perspective view of a first embodiment of a suture bridge showing our new design;

FIG. 2 is a top plan view thereof;

FIG. 3 is a bottom view thereof;

FIG. 4 is a front view thereof;

FIG. 5 is a back view thereof;

FIG. 6 is a right side view thereof;

FIG. 7 is a left side view thereof;

FIG. 8 is a front perspective view of a second embodiment of a suture bridge showing our new design;

FIG. 9 is a top plan view thereof;

FIG. 10 is a bottom view thereof;

FIG. 11 is a front view thereof;

FIG. 12 is a back view thereof;

FIG. 13 is a right side view thereof;

FIG. 14 is a left side view thereof;

FIG. 15 is a front perspective view of a third embodiment of a suture bridge showing our new design;

FIG. 16 is a top plan view thereof;

FIG. 17 is a bottom view thereof;

FIG. 18 is a front view thereof;

FIG. 19 is a back view thereof;

FIG. 20 is a right side view thereof; and,

FIG. 21 is a left side view thereof.

It is noted that any broken line illustration of environmental structure in the drawing is not part of the claimed design.
